UNITED STATES PATENT OFFICE.

HORACE E. GREENWOOD AND JOHN W. GRANTLAND, OF PHILADELPHIA,
PENNSYLVANIA.

WATER-CLOSET.

SPECIFICATION forming part of Letters Patent No. 533,846, dated February 5, 1895.

Application filed September 10, 1894. Serial No. 522,573. (No model.)

To all whom it may concern:

Be it known that we, HORACE E. GREENWOOD and JOHN W. GRANTLAND, citizens of the United States, residing at the city of 5 Philadelphia, in the county of Philadelphia and State of Pennsylvania, have jointly invented certain new and useful Improvements in Water-Closets, of which the following is a specification.

10 Our invention has relation to a water-closet in which a removable lid or seat is employed in connection therewith; and it relates more particularly to the construction and arrangement of the water-closet bowl provided with 15 pockets or sockets and to a lid or seat provided with a knuckle-jointed swiveling spring device adapted to removably engage the pockets or sockets of said bowl to permit not only of the raising and lowering of the lid or seat, 20 but also of the ready removal of the same from the bowl.

The principal objects of our invention are first, to provide a simple, durable and effective water-closet with a lid or seat so arranged 25 as to be readily removed from the same; second, to provide a water-closet bowl with recessed pockets or sockets and a lid or seat or both hinged to each other and provided with a knuckle-jointed swiveling spring clamping 30 device adapted to detachably seat with the pockets or sockets of said bowl; third, to provide a spring clamping device with concealing strips or flaps having a swiveling knuckle-jointed plate adapted to be secured to a lid 35 or seat and of the said clamping device to engage pockets or sockets of a water-closet bowl in such manner as that the same can be instantly removed for cleaning and other purposes and at the same time so arranged as 40 that in its engagement with the sockets or pockets of the bowl there is permitted a raising and lowering of the lid or seat or both; fourth, to provide a spring clamp connected by a knuckle-joint with a lid or seat and 45 adapted to engage a pocket or socket of the water-closet bowl having side and top entrance openings; and fifth, to provide a water-closet in which a lid or seat removably engages recessed pockets or sockets formed in 50 rear projections of the bowl in order to afford not only an ease of movement of the lid or

seat or both in the connection established with the bowl, but also a quick removal of the lid or seat or both hinged together therefrom.

55

Our invention stated in general terms, consists of a water-closet bowl provided with pockets or sockets for the reception of spring clamping devices having swiveling knuckle-jointed connections with a lid or seat, whereby 60 the lid or seat or both may be removed from the pockets or sockets of said bowl for cleansing and maintaining the water-closet in a thoroughly good sanitary condition; and our invention further consists of the improvements 65 in water-closets hereinafter described and claimed.

The nature and characteristic features of our invention will be more fully understood 70 from the following description taken in connection with the accompanying drawings forming part hereof, and in which—

Figure 1, is a perspective view of the rear portion of a water-closet bowl, showing one of the pockets or sockets thereof and also a 75 lid and seat hinged to each other, and the latter provided with a knuckle-jointed swivel connection with a spring clamping device having concealing strips and depending fingers, the latter adapted to prevent sidewise 80 movement in the engagement of the said clamping device with the pockets or sockets of said bowl. Fig. 2, is a view partly in section and partly in elevation of a slightly modified form of spring clamping device af- 85 forded two different motions in the connection of the same with a lid or seat and in the engagement of the said device with the recessed pockets or sockets of the water-closet bowl; and Fig. 3, is a rear view of the lid and 90 seat and a transverse sectional view through one of the pockets or sockets of the water-closet bowl and of the spring clamping device of Fig. 2, for establishing a removable connection of the lid and seat with the wa- 95 ter-closet bowl.

Referring to the drawings with reference more particularly to Fig. 1, *a*, is the rear portion of a water-closet bowl provided with end recessed pockets or sockets *a*², having top and 100 side entrance openings *a*³ and *a*⁴, leading into the same, and the said pockets or sockets be-

ing preferably of the shape or configuration illustrated.

b, is the lid and *b'*, is the seat hinged thereto at *b'*, in any preferred manner.

5 *c*, is a plate screwed to the bottom of the seat *b'*, and provided with a knuckle-joint connection *c'*, having a threaded stem or shank *c²*, engaging a complementally threaded truncated cone or other shape cap formed 10 preferably with a right angular concealing strip *c³*, with rounded inner and lower ends *c⁴* and *c⁵*.

15 *c⁶* and *c⁷*, are depending fingers secured to or formed integral with the top and side plates of the concealing strip *c³*. Between the fingers *c⁶* and *c⁷*, is provided a steel or other metal spring clamp *C*, comprising two jaws *c⁸* and *c⁹*. Flaring outwardly and curving inwardly toward the base ends thereof and 20 extending crosswise between the two jaws of the clamp *C*, is inserted a pin or rod *c¹⁰*, for strengthening the upper inner end of the jaws of the clamping device and also to hold the jaws apart required distances so as to insure 25 a proper springing action of the same into engagement with the complementally arranged recessed pockets or sockets *a²*, of the water closet bowl *a*, and the fingers *g⁶* and *g⁷*, of the spring clamping device *C*, arranged as shown 30 in Fig. 1, prevent sidewise movement of the spring jaws *c⁸* and *c⁹*, thereof in engagement with the pockets or sockets of the bowl *a*.

In Figs. 2 and 3, the pockets or sockets of 35 the water-closet bowl *a*, are the same in construction and arrangement as in Fig. 1, and the lid *b*, is hinged to the seat *b'*, in the same manner as hereinbefore explained with reference to Fig. 1, of the drawings, but the spring clamping device differs from that of 40 Fig. 1, in the following manner: The plate *c*, screwed to the bottom of the seat *b'*, is provided with a circular perforated tongue *c¹²*, engaging between spherical bearings *c¹³* and *c¹⁴*, to constitute by the pivotal connection of the 45 said tongue therewith a knuckle-joint connection *c'*, and the spherical bearings *c¹³* and *c¹⁴*, are provided with a tapering base *c¹⁵*, seating in a complemental bearing *c¹⁶*, of the flanged top-plate *c¹⁷*, of the concealing strip 50 *c³*. This base *c¹⁵*, is held to position in its bearings *c¹⁶*, by means of a plate *c¹⁸*, provided with depending integral fingers *c⁶* and *c⁷*. The plate *c¹⁸*, seats in the recessed under portion of the flanged top plate *c¹⁷*, by means of 55 a screw *c¹⁹*, and one of the said fingers is held to position against the side plate *c⁸*, of the concealing strip *c³*, by means of a screw *c²⁰*, as clearly illustrated in Fig. 3. The clamp 60 consists of two spring metal jaws *c⁸* and *c⁹*, of the same form or shape as those of Fig. 1, and are inserted and supported to required position between the fingers *c⁶* and *c⁷*, in the manner hereinbefore described.

The arrangement of the swiveling spring 65 clamping device *C*, in Figs. 2 and 3, permits of a free back and forth movement of the lid with a seat hinged thereto, as well as a free

turning around of both of said members in the readily removable connection of said device with the recessed pockets or sockets *a²*, 70 of the bowl *a*.

Among the advantageous features of our invention may be mentioned the fact, that the lid with its seat having the swiveling spring clamp connection removably established with the pockets or sockets of the water-closet bowl insures perfect working of the lid and its seat, as well as a quick removal of both hinged members from the bowl for thoroughly cleansing the water-closet with 80 the least amount of time and labor of maintaining the closet in a perfectly good sanitary condition from a hygiene standpoint.

It will be manifestly obvious to those skilled in the art to which our invention 85 pertains, that as to minor details modifications in the form or shape of the spring clamping device may be made, without departing from the spirit of the invention.

Having thus described the nature and objects of our invention, what we claim as new, and desire to secure by Letters Patent, is—

1. A water-closet bowl provided with pockets or sockets, a lid or seat, a knuckle-jointed connection, one member of which is attached 95 to said lid or seat and the other member having concealing strips and clamping jaws engaging the pockets or sockets of said bowl, substantially as and for the purposes described.

2. A water-closet bowl provided with recessed pockets or sockets having top and side entrance openings, a lid or seat, and a knuckle-jointed connection, one member of which is attached to said lid or seat and the other having spring clamping jaws detachably engaging said pockets or sockets, substantially as and for the purposes described.

3. A water-closet bowl provided with pockets or sockets, a lid or seat, a concealing strip 110 a knuckle-jointed connection, one member of which is attached to said lid or seat and the other detachably connected with said concealing strip and depending spring clamping jaws and fingers, substantially as and for the purposes described.

4. A water-closet bowl provided with recessed pockets or sockets, a lid or seat, a concealing strip having spring metal jaws movably engaging said pockets or sockets, a 120 knuckle-jointed connection, one member of which is secured to said lid or seat and the other by a swivel joint connected with said concealing strip, substantially as and for the purposes described.

5. A water-closet bowl provided with pockets or sockets, a lid or seat, a knuckle-joint connection, one member of which is secured to said lid or seat and the other member provided with two spring clamping jaws and fingers engaging said pockets or sockets, substantially as and for the purposes described.

6. A water-closet bowl provided with pockets or sockets, a lid or seat, an angular plate

having fingers, a knuckle-joint connection, one member of which is secured to said lid or seat and the other member swiveling in said angular plate and spring clamping jaws engaging said pockets or sockets, substantially as and for the purposes described.

In testimony whereof we have hereunto set

our signatures in the presence of two subscribing witnesses.
